SPECIFICATION forming part of Design No. 31,568, dated September 26, 1899.

Application filed August 30, 1899. Serial No. 729,016. Term of patent 14 years.

To all whom it may concern:

Be it known that I, GEORGE S. HENSEL, a citizen of the United States, residing in the city and county of Philadelphia, State of Pennsylvania, have invented and produced a new and original Design for a Skirt-Protector, of which the following is a specification, reference being had to the accompanying drawings, forming part thereof.

10 The leading feature of my design for a skirt-protector is a head, a brush pendent therefrom, a series of ribs on the face of said head above the brush, and a rib on said face adjacent to the upper edge thereof.

15 Figure 1 represents a side elevation of a skirt-protector embodying my design. Fig. 2 represents a section thereof on line x x , Fig. 1.

In the drawings, A designates a piece of skirt-protector, the same consisting of the 20 head B, the brush C pendent therefrom, the differential ribs D on the face of said head above said brush, and the rib E on said face below the upper edge thereof, said ribs D and E extending in the direction of the length of 25 the head.

Having thus described my invention, what I claim as new, and desire to secure by Letters Patent, is—

The design for a skirt-protector substantially as shown and described. 30
